UNITED STATES PATENT OFFICE.

PARMER DORSEY, OF WICHITA, KANSAS, ASSIGNOR TO THE IMPERIAL BRASS MANUFACTURING COMPANY, OF CHICAGO, ILLINOIS, A CORPORATION OF ILLINOIS.

LUBRICATOR.

Application filed November 23, 1922. Serial No. 602,707.

My invention is concerned with lubricators designed primarily for use with engines, and more especially with locomotive engines, and is designed to produce a sight-feed lubricator 5 that can be quickly filled when necessary from a supply reservoir without substantially distracting the engineer from his work of watching the roadbed ahead of him.

My invention is further concerned with certain novel constructions in said devices, all as will be fully described in the specification and particularly pointed out in the claims.

To illustrate my invention, I annex hereto
15 two sheets of drawings, in which the same
reference characters are used to designate
identical parts in all the figures, of which, —

Fig. 1 is a side elevation of a portion of a locomotive having a lubricator embodying my invention applied thereto;

Fig. 2 is a side elevation of the supply reservoir and the associated hand pump which I preferably employ;

Fig. 3 is a central, vertical longitudinal section through the supply reservoir and the associated pump;

Fig. 4 is a top plan view in section on the line 4—4 of Fig. 3;

Fig. 6 is a top plan view of a portion of the apparatus illustrating a modified construction;

Fig. 7 is a section on the line 7—7 of Fig. 35 6; and

Fig. 8 is an elevation of a fulcrum ring.

Referring first to Fig. 1, 10 is the boiler of

a locomotive engine having the engineer's cab 11 thereon arranged in the customary manner, and on the side of the boiler toward the end I locate the sight-feed reservoir 12, which

has the condenser dome 13 on the top thereof, which is connected by the pipe 14 with the interior of the boiler 10 above the water line.

boiler, I fasten the pump 16, which supports the supply reservoir 17 from which it draws oil to fill the sight-feed reservoir 12, being connected thereto by the pipe 17a.

50 The condenser dome 13 is of any desired construction, and is secured to the reservoir

12 to co-operate therewith in the customary manner.

The auxiliary reservoir 17 preferably consists of a metallic cup of considerable size, the top of which is preferably closed by the cap 48 preferably screwed thereon and provided with the knob 49 preferably having the air passage 50 therethrough. To strain the oil and prevent any dirt possibly passing to the engine, I locate in the bottom of the cup 17 the ring 51, of a diameter to fit the interior of the cup and having the fine-mesh metallic screen 52 secured in the top thereof. Conveniently to remove the screen, I secure in the center thereof the rod 53 terminating in the handle 54. The bottom of the cup is provided with the centrally located projection 55, the lower end of which is threaded and screwed into the threaded upper end of the projection 56 extending up from the pump body 16. The pump barrel 16 has the inlet 64 in the top thereof and opening substantially in the center of the cylinder bore 65, with which co-operates the piston 66, which is preferably a solid plunger, which has the rod 67 formed integral therewith and extending through the packing 68 held in place by the washer 69 resting against the annular shoulder 70 formed at the end of the cylinder bore, and by the opposed packing cylinder 71, which is forced against the packing by the gland 72 screwed on the threaded end of the cylinder. The end of the piston rod has the fork 73 screwed thereon and forming ears to which the hand lever 74 is connected by the pin 75 passing through one of the ears and screwed into the other and extending through the slot 76 in the end of the lever 74 if said lever extends downwardly as shown in Figs. 1 and 2. The fulcrum of the lever is formed by the link 77 pivoted thereto at 78 at one end, and between the ears 79 formed on the

under side of the barrel 16. This barrel also has on the under side the lugs 80 resting on the bracket 15 and secured thereto by the screws 81 passed through the bracket and screwed into the lower end of the lugs 80. The other end of the barrel has the reduced passage 82 extending from the bore and into the larger passage in the end thereof, which end is secured to the end of the pipe 17^a by

the connecting nut 84 in the customary manner. The outlet is provided with the tapered valve seat 85 with which co-operates the check valve 86, which valve is held normally closed by the helically-coiled expanding spring 87 co-operating therewith and with the annular shoulder formed in the end of the pipe 17^a. A passage 88 is drilled from the shoulder 70 to a point above the inlet port 64 so that as 5 the piston head 66 is reciprocated back and forth, the oil caught by the rear of the piston can escape back to the inlet 64. The pipe 17^a terminates in the angle cock 90 which 10 open into the connection 23 to the reservoir 12. 15 In order to show the advantage of my improved construction, I will first describe the process of filling such a sight-feed reservoir 12 as practiced prior to my invention: When it becomes necessary to fill the reservoir, it is 20 full of water, and the first thing that has to be done is to close all the valves associated therewith controlling the delivery of the oil therefrom and the steam pressure thereto. Then the drain cock and an oil-inlet plug in 25 the top of the reservoir were opened when the water will run out. With the water discharged, the drain cock is closed and the oil poured in slowly through the oil inlet until the reservoir is full, when the oil inlet is 30 closed and the water of condensation from the boiler permitted to enter by opening the cock between the reservoir 12 and the condenser dome 13. The adjustments for the valves for the different sight feeds having 35 been destroyed by closing them, the engineer now has to readjust these valves carefully by timing the number of drops per minute that rise through each of the sight feeds. This takes time, has to be carefully done, and dis- 40 tracts his attention from the track and signals. With my improved invention, the sight-feed valves do not have to be disturbed. The valves in the discharge outlets from the reservoir 12 may be closed; the angle cock 90 45 is opened, and the pump handle 74 worked a few times or until the oil and water line appears in the lower sight glass located at the bottom of the reservoir 12. The oil forced in by the pump forces the water in the reservoir 50 12 through the dome 13 and the pipe 14, back into the boiler 10, thus obviating any possibility of any scalding resulting from careless manipulation of the apparatus or leaky valves. When the pumping is finished, 55 the cock 90 is closed, the valves in the discharge outlets from the reservoir 12 are opened, if they had been closed, and the lubrication proceeds automatically just as before without in any way disturbing the adjustment of the various feeds. If it is desired to 60 furnish extra oil to any cylinder, it can be done by closing the cock between the reservoir 12 and the dome 13 and opening the outlet valve leading from the reservoir 12 to that 65 particular cylinder, closing the other outlet

valves, and a stroke or two will furnish the desired extra oil, after which the other outlet valves can be opened, the cock between the reservoir 12 and the dome 13 opened, and the lubrication proceed as usual.

In the construction so far described, it is necessary to mount the handle 74 so as to swing in a vertical plane. In some cases, however, it is desirable to make it swing in some other plane than a vertical plane, such as a horizontal plane or any other angle, and for this purpose I employ the modification shown in Figs. 6, 7 and 8, where, instead of the lug 79, I employ the fulcrum ring 91, which has the ear 92 on which the link 77 is pivoted. This ring 91 is clamped at any desired angle between the washer 93 abutting against a shoulder 94 on the barrel 16 and the nut 95, which is screwed on the elongated threaded end of the pump barrel inside of the packing nut 62. While I have shown the packing 68 as unnecessarily elongated, it will be understood that it could be shortened by moving the shoulder 70 farther out toward the end of the threaded portion. With this construction, it will be obvious that the handle 74 can be set at any desired angle which convenience of location and operation may require.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a lubricating pump, the combination with a barrel having a central inlet, of a check valve in the outlet of the barrel, a piston in the barrel, a piston rod extending through the other end of the barrel, packing for said piston rod, and a channel in the barrel extending from the inlet to the packing.

2. In a pump, the combination with a pump barrel having a threaded end, of a piston mounted to reciprocate therein, a piston rod connected thereto, a lever pivoted to the end of the piston rod, a fulcrum ring on the threaded end of the barrel, a packing nut threaded on said end, an annular abutment on the barrel against which the fulcrum ring is held, and a nut on the threaded portion of the barrel co-operating with the fulcrum ring to hold it in any desired angular position thereon to determine the plane in which the lever swings.

3. In a lubricator, the combination of a cylinder having a discharge port; a reservoir surmounting the same; a piston mounted for reciprocation in the cylinder, a piston rod extending outwardly from the piston and

through the rear portion of the cylinder; and a packing surrounding the rod adjacent the rear end of the cylinder and serving to prevent the passage of oil outwardly along the rod, the reservoir being provided with two laterally extending ports opening directly into the cylinder adjacent the opposite ends thereof, that port located adjacent the rear end of the cylinder being in free communication therewith and with the reservoir at all times.

In witness whereof, I have hereunto set my hand this 7th day of November, 1922.

PARMER DORSEY.
